UNITED STATES PATENT OFFICE.

CHARLES HILLER, OF ST. LOUIS, MISSOURI, ASSIGNOR OF ONE-HALF TO SAMUEL G. STAHLHUTH, OF ST. LOUIS, MISSOURI.

HOT-AIR FURNACE, STOVE, AND THE LIKE.

1,340,340.

Specification of Letters Patent. Patented May 18, 1920.

Application filed May 3, 1919. Serial No. 294,500.

To all whom it may concern:

Be it known that I, CHARLES HILLER, a citizen of the United States, and resident of St. Louis, Missouri, have invented certain new and useful Improvements in Hot-Air Furnaces, Stoves, and the like, of which the following is a specification.

This invention relates to improvements in hot-air furnaces, stoves and the like, and 10 has for its object an inner heating compartment consisting of a sheet of metal bent and shaped to form a plurality of diving flues, a lining placed therein and covering a portion of said flues and detachable frame 15 shields placed on the top of the shell and against the contacting walls of the diving flues.

A further object of my invention is to 20 construct a heating apparatus such as hot-air furnaces, heating stoves and the like, the same consisting of an inner shell and an outer housing, the inner shell being bent and shaped to form a plurality of diving flues, a lining placed therein and covering 25 a portion of said flues, detachable frame shields placed on the top of the shells and against the contact walls of the diving flues, a fire box located in said shell and an ash-pit below the fire box, the diving flues being 30 arranged for equally distributing the heat in the entire compartment and for directing the heat downward passing under the base of the inner compartment.

Figure 1, is a horizontal sectional view 35 taken on the line 1—1 of Fig. 2.

Fig. 2, is a vertical sectional view taken on the line 2—2 of Fig. 1.

Fig. 3, is a side view of my invention with the outer casing removed.

Fig. 4, is a rear perspective view of one 40 of the detachable flame shields made use of.

Fig. 5, is a detail sectional perspective view of the damper mechanism made use of.

In carrying out my invention I provide 45 a heating apparatus constructed of an inner compartment consisting of a wall or shell 6, which is bent, shaped or cast into a plurality of diving flues and preferably in the number as shown in the illustration.

50 In order to obtain the proper result of equally distributing the heat I shape the diving flues into various sizes. The flue 7 is the smallest in width, the flue 8 slightly larger and the flue 9 the greatest in width.

55 The depth of the flues is the same. These flues extend from the top 10 to the bottom

11; the bottom ends of the flues being securely connected to the bottom 11 while the tops are provided with a cover 12, which forms a part of the top 10 and is either riveted or welded so as to make an absolute gas-proof joint; in fact all of the joints are so constructed as to prevent gas or smoke from escaping and from passing into the outer casing 13.

60

In the inner compartment is placed a fire-box 14, which is arranged by first placing into the compartment a sheet metal shell 15, which extends upwardly to a height sufficient to provide a proper depth for the 70 fire box. In this shell is supported the usual grate-bars 16, the bottom 17 of the shell forming the bottom of the ash-pit 18, this bottom being located a short distance above the bottom 11, so as to allow a reasonable space 19 for the circulation of hot 75 air near the ash-pit 18, as well as to form a clean-out opening from which all sediment, such as dust or soot might be removed from the inner compartment.

80

This clean-out opening is provided with an inlet 20, provided with a door 21 through which access may be had to the compartment, the ash-pit 18 being provided with an inlet 22 provided with a door 23, through 85 which the ashes may be removed from the ash-pit.

Against the shell 15 and above the grates 16, I place a lining 24 of fire-clay which forms the proper lining for the fire-box, 90 and leading into the fire box is a fuel inlet 25, provided with a fire door 26.

The arrangement of the diving flues as will be observed extend from the top to the bottom and extend a reasonable distance 95 above the top of the fire box so that all particles of combustion are directed to the openings of the diving flues and pass down through these openings to the bottom or base of the casing and then directed to the rear 100 into the flue 27, from which it escapes through the outlet 28 into the chimney. The action is a down-draft arrangement and all the heat and particles of combustion must pass downwardly through the diving flues 105 before reaching the chimney; and by means of increasing the size of the diving flues from the rear to the front it equally distributes the heat within the chamber 29 which is formed between the inner compartment and 110 the outer casing 13.

In order to prevent the excessive heat

- and flame from burning through the portion 30 of the material from which the diving flues are constructed I place over the same and immediately upon top of the fire-clay, 5 detachable flame shields 31, the structure of these are clearly shown in Fig. 4. It is preferably constructed of a casting so arranged as to conform with the shape of the portion 30 of the diving flues and is provided with 10 a pair of depending projections 32 which pass down on the outside of the shell 15 against which the fire-clay is supported; and the edge or shoulder 33 resting upon the top of the same. This acts as a shield as 15 well as a preventive from burning through the material at that point.

These shields may be arranged to suit by building the same any height desired, this 20 greatly depends upon the general structure of the apparatus and the circulation of the heat.

On the top of the flue 27 and above the outlet 28, is an opening 34 which is provided with a damper 35, the detail of construction 25 being shown in Fig. 5. This damper is supported on brackets 36 located on the sides of the box, and the damper is controlled by the rod 37 (see Fig. 5) which passes through the flue casing and also through the outer 30 casing but in a manner as that shown by dotted lines in Fig. 1. This damper is only used when starting a fire so as to give the fire a direct draft and when the fire has been properly started the damper is then closed 35 and remains closed so as to direct all heat and particles of combustion downwardly before passing to the chimney.

One of the features of my invention is to 40 provide a heat generating compartment to be centrally located in the outer shell so as to direct an even amount of heat at the rear, sides and front and also at the base. By this arrangement the pipes which lead from the openings 38 formed in the top of the

outer casing 13, are provided with an equal 45 amount of properly heated air and every room to be heated is properly provided with its share of heat.

It has been found that heaters of the present structure have the outer casing arranged 50 eccentric to the inner compartment thereby some of the heat distributing pipes leading to the outer compartment are not properly provided with circulation and furthermore the present form of heaters direct their heat 55 toward the rear and very little toward the front. This obstacle is dispensed with in my invention as the heat is equally distributed within the entire apparatus.

Having fully described my invention what 60 I claim is:

A furnace of the class described, comprising an inner heating compartment consisting of a shell of sheet material bent and shaped to form a plurality of diving flues, a lining 65 placed therein and covering a portion of said flues, detachable flame shields placed on the top of the shell and against the contacting walls of the diving flues, a fire-box located in said shell, an ash-pit below the fire 70 box, an outer compartment incasing the inner heating compartment which inner compartment is located centrally therein, the diving flues being arranged for equally distributing the heat in the entire outer compartment and for directing the heat downwardly passing under the base of the inner compartment before entering the chimney and a damper for permitting a direct draft to the fire-box when first kindling the fire, 75 substantially as specified.

In testimony whereof, I have signed my name to this specification, in presence of two subscribing witnesses.

CHARLES HILLER.

Witnesses:

ALFRED A. EICKS,
B. AUSTINE.
